CLAIM

The ornamental design for a perforated roll of placemats, as shown and described.

DESCRIPTION

FIG. 1 is a front and left side perspective view of a perforated roll of placemats showing my new design; and, FIG. 2 is a rear and left side perspective view thereof, showing my new design, with the right side constituting a mirror-image of the left side.

The placemats in the roll are understood to be of conventional thickness. The undisclosed top side and bottom side of the placemats in the roll is plain and unornamented.
